UNITED STATES PATENT OFFICE.

EMERY E. LA DUKE, OF SALT LAKE CITY, UTAH.

CENTRIFUGAL BASKET.

1,394,743.

Specification of Letters Patent. Patented Oct. 25, 1921.

Application filed August 2, 1921. Serial No. 489,242.

To all whom it may concern:

Be it known that I, EMERY E. LA DUKE, a citizen of the United States, residing at Salt Lake City, in the county of Salt Lake 5 and State of Utah, have invented certain new and useful Improvements in Centrifugal Baskets, of which the following is a specification.

My invention relates to centrifugal 10 baskets, and has for its object to provide a basket to be rapidly rotated on its vertical axis whereby liquid may be strained and clarified of dirt and other similar substances by centrifugal force, and the clarified liquid 15 drawn off for use, and particularly to strain and clarify gasoline and other cleaning fluids commonly used to clean articles of clothing, and also to clarify the gasoline and other liquids used in garages in washing 20 machinery and other parts of automobiles in making repairs.

These and other objects which will be apparent I accomplish with the device illustrated in the accompanying drawings, in 25 which similar letters and numerals of reference indicate like parts throughout the several views, and as described in the specification forming a part of this application and pointed out in the appended claims.

30 In the drawings in which I have shown a substantial embodiment of my invention, Figure 1 is an elevation of the basket. Fig. 2 is a plan view of the flange therein. Fig. 3 is a vertical diametric section of a centrifugal casing, showing one of my baskets 35 in place therein and with the pulley and shaft of the basket shown in the base of the centrifugal casing.

In washing clothing and machinery with 40 gasoline and other similar liquids, the liquid soon carries quantities of dirt, metal particles, carbon atoms and other matter, so much so that said liquid cannot be used for like purposes until it has been strained and 45 clarified of such foreign matter, and such clarifying if at all practical must be done quickly and economically. The present invention is intended for such use and consists of a metal cup-shaped basket A which 50 is mounted for rapid rotation within a casing B. The said basket A to be driven by power applied to its axial shaft 1 through the pulley C, but as will be obvious, power for rotating the basket may be applied on or 55 through a depending shaft. The bottom and a portion of the side wall of said basket is

liquid tight, while the remaining portion of the side wall has holes or perforations 2 therein. An inwardly turned annular flange 3 is secured on or to the inner wall of said basket A at or near the lower edge of the perforations 2 in the basket wall. A plurality of perforations 4 are provided through the said annular flange 3.

The operation of my invention is as follows:—With power to rapidly rotate said basket within its casing B, the liquid to be strained and clarified is poured or allowed to flow through the top of said casing B by removing its cover 5, into the basket A. 70 Centrifugal motion will be imparted to said liquid and any particles having a specific gravity greater than the liquid whether soluble or insoluble will be carried downwardly by gravity and outwardly by the centrifugal force generated and will accumulate 75 and be deposited in a layer on the bottom and imperforate portion of the side wall of the basket, while the clarified liquid will be forced out through the perforations 4 of the 80 annular flange 3 and the perforations 2 of the basket, and will be caught in the lower portion of said casing B and be drawn off through the drain cock 6 provided therefor. The operation may be continued if desired 85 until the layer of waste matter accumulates in sufficient quantities and thickness as to stop the perforations 4 of the flange 3, then the basket is to be cleaned out. I have found that some deposit of solid matter will be 90 found on the inner wall of said basket above the flange 3, having passed through the perforation 4 of the flange, and I therefore continue the separation above the flange 3 by perforating the upper portion of the wall of 95 the basket as shown at 2, and particularly coloring matter such as unburned carbon or soot and discolored light oil will be caught within the basket and above the flange.

I thus provide a new and novel centrifugal basket improved for the new use of clarifying liquids, and by closing the perforations commonly found in the lower portions of the wall of such baskets, and also by providing an inwardly turned annular flange 105 to be rotated with and by the basket.

Having described my invention I desire to secure by Letters Patent and claim:—

1. In a centrifugal basket the combination with a stationary casing of a cup-shaped 110 metal basket having perforation in the upper portion of its side wall; and a flange member

secured on the inner wall of said basket adjacent the lower of said perforations.

2. In a centrifugal basket the combination with a casing; a closure therefor; a cup-shaped metal basket having perforation in the upper portion of its side wall; an annular flange having perforations therein and which is fastened in said basket adjacent the bottom row of perforation in the wall of 10 said basket; and means to rotate said basket on its vertical axis.

3. A centrifugal basket for clarifying liquids comprising a cup-shaped member having its upper portion perforated; and 15 an inwardly turned flange therein having

perforation in the inturned portion; with means to rotate said basket within a casing.

4. In a machine of the class described comprising a stationary casing; a cup-shaped basket with the upper portion of its side wall 20 perforated and mounted for rotation in said casing; means to drain said casing; an inwardly perforated flange member at the bottom of the perforations of said casing; and means to rotate said basket within said casing for the purposes described. 25

In testimony whereof I have affixed my signature.

EMERY E. LA DUKE.
